UNITED STATES PATENT OFFICE

WAYNE JENKINS, OF LOS ANGELES, CALIFORNIA

DESIGN FOR A GAS STOVE COMBINED MANIFOLD COVER AND CONTROLS

Application filed March 22, 1932. Serial No. 43,261. Term of patent 14 years.

To all whom it may concern:

Be it known that I, WAYNE JENKINS, a citizen of the United States, residing at Los Angeles, in the county of Los Angeles, State of California, have invented a new, original, and ornamental Design for a Gas Stove Combined Manifold Cover and Controls, of which the following is a specification, reference being had to the accompanying drawing, forming a part thereof.

In the drawing, Fig. 1 is a front face view of a combined manifold cover and control,

the positions of associated gas cock handles being shown in dotted lines and a control handle conforming thereto in full lines. Fig. 2 is a section as seen on the line 2—2 of Fig. 1. It will be understood that the geometrical outlines of the gas cock and control handle are nonessential.

I claim:

The ornamental design for a gas stove combined manifold cover and controls as shown and described.

WAYNE JENKINS.
